UNITED STATES PATENT OFFICE.

DAVID ALBERT VICTOR RIST, OF NEW SOUTHGATE, LONDON, ENGLAND.

COIL-IGNITION APPARATUS FOR INTERNAL-COMBUSTION ENGINES.

Application filed May 31, 1921. Serial No. 474,001.

To all whom it may concern:

Be it known that I, DAVID ALBERT VICTOR RIST, of Victoria Works, South Road, New Southgate, London, England, whose post office address is Victoria Works, South Road, New Southgate, London, England, a subject of the King of Great Britain, have invented certain new and useful Improvements in or Connected with Coil-Ignition Apparatus for Internal-Combustion Engines, of which the following is a specification.

This invention for improvements in coil ignition apparatus for internal combustion engines has for its object to provide a compact ignition unit including an induction coil contact breaker, distributor and condenser, that shall be simple in construction, highly efficient and readily applicable in place of magnetos as at present used.

Another object is to enable the coil to be rendered inoperative at will and locked in the inoperative condition with a view to preventing theft of or the unauthorized use of any vehicle upon which it may be employed.

A further object is to enable stampings to be used for incasing or housing the principal parts thereby facilitating production or standardization.

It has been proposed to construct a coil ignition unit comprising two or more vertical shafts carrying the moving parts of distributor and timing mechanism and geared with a horizontal drive shaft, the shafts together with the distributor and timing mechanism being enclosed in a housing capable of being seated on the usual magneto base.

According to the present invention, the drive and distributor shafts of the igniter are mounted horizontally and parallel with one another and the coil which is also horizontally disposed, the condenser, and the driving gear of the distributor and contact breaker including the aforementioned shafts, are enclosed in a casing or housing the arrangement being such that the induction or sparking coil only requires at most two external wires for the low tension circuit all the other low tension wires being enclosed in the housing or cover of the apparatus.

The casing is also provided with a connector for a lamp and with a locking de-

vice with key arranged to separate contacts in the casing to break the low tension circuit and thus render the coil inoperative when desired.

In a practical form of construction the 60 casing or housing is mounted on a magneto type of base above which the drive shaft and distributor shaft geared thereto to revolve at half the speed of the engine shaft are mounted in ball bearings. The coil is 65 supported above and parallel with the shafts, the shafts and coil being disposed horizontally in the casing whilst the distributor and contact breaker which are also horizontally disposed are either inside or 70 outside the casing. It is important that the condenser should be housed in the casing and it is preferably placed just above the base.

The lock comprises a bolt or movable 75 member controlled by a key and arranged to act on one of a pair of spring contact blades.

A visual indicator such as a lamp may be provided to give an indication if the primary circuit of the ignition should be left closed when the engine is stopped, and a switch operated by thermostatic, magnetic, or mechanical means may also be provided for opening the circuit to prevent the exhaustion of the battery.

It will readily be understood that the ignition apparatus as described is well adapted for use on cars equipped with electric lighting sets where it can be installed with 90 advantage in place of the magneto and has in the storage battery a constant and reliable source of current.

In the accompanying two sheets of illustrations, 95

Fig. 1 is a side elevation of coil ignition apparatus constructed according to this invention.

Fig. 2 is an end elevation of the same.

Fig. 3 is a longitudinal sectional elevation.

Fig. 4 is a similar view to Fig. 2 but with the insulating cap portion of the distributor removed.

Fig. 5 is a transverse section at 5—5 105 Fig. 3.

As shown the ignition unit is made so as to be interchangeable with a magneto without requiring any alteration in the engine arrangements and comprises a casing or 110

housing constructed of end plates *a*, *a'* cover *b* and base *c* all capable of being formed of stampings or pressings.

On the end plates are welded or otherwise fixed housings *d*, *d*', *d*", *d*'' for ball bearings in which two horizontal shafts *e* and *f* are journaled, the shaft *e* being referred to as a distributor shaft and the shaft *f* as a drive shaft, the two shafts being geared together by these spur wheels *g*, *g*' to actuate the distributor *h* and contact make-and-break *i* which are of any suitable construction.

It will be seen that the arm *h*' controlling the advance and retard comes into the same position as it would on the contact maker of a magneto and no extra mechanism is necessary for the operation of this arm.

The insulating cap portion of the distributor is held on by two spring catches *u* and can be easily removed by pressing back the catches.

In the bottom of the casing just over the base is fitted the condenser *j* which only requires a very short connection *j*' an important advantage in avoiding electrical leakage.

At the upper part of the casing above the shafts the coil *k* is supported horizontally for which purpose it is provided with hook ended bar *l* engaging over horizontal rods *m* extending between the end plates. From the high tension circuit runs a single heavily insulated lead *n* with plug *o* which is inserted in a socket or sleeve in the centre of the distributor.

For the purpose of locking the ignition unit against use by any unauthorized person a lock *p* of the Yale type is arranged to open and close a switch on the distributor end of the casing the barrel of the lock carrying a pinion *q* engaging with a movable rack *r* mounted to slide in a slotted bar and carrying a striking piece *s* of insulating material fixed to the rack by screws, the striking piece being moved against or away from one of a pair of contact blades *t* to close or separate the contacts.

On one end plate of the casing a plug socket *v* for an inspection lamp is arranged

through which current is conveniently obtained from the distributor or coil connection when a light is required for use round or about the engine.

I claim:—

1. A coil and distributor unit for mounting in place of the magneto of an internal combustion engine and comprising a housing, a distributor and circuit breaker secured against one end of said housing, a driven shaft rotatably mounted in said housing and extended through one end of said housing for connection with the magneto operating shaft of an engine, a distributor operating shaft rotatably mounted in said housing and rotated from said drive shaft and extending through the other end of said housing for operating said distributor and circuit breaker when rotated, a fixed sparking coil mounted in said housing and having operative connection with said distributor, said coil being supplied with current from a storage battery, and a condenser mounted in said housing and having operative connection with said coil.

2. A coil and distributor unit for mounting in place of the magneto of an internal combustion engine and comprising a housing having forward and rear walls, a distributor mounted upon the outer face of the forward wall, a fixed sparking coil in the upper portion of said housing, a conductor extending from said coil out of said housing and provided with a terminal plug having connection with the distributor, a distributor shaft in said housing beneath said coil extended through the forward wall for operating said distributor when rotated, a drive shaft in the housing beneath the distributor shaft and operatively connected with the distributor shaft for imparting rotary movement to the same and extended through the rear wall for connection with the magneto operating shaft of an engine, and a condenser in the lower portion of the housing and having operative connection with said coil.

In testimony whereof he has affixed his signature.

DAVID ALBERT VICTOR RIST.
